BALZ-ERZROSTUNG GESELLSCHAFT MIT BESCHRAENKTER HAFTUNG, OF GLEIWITZ,
GERMANY

MECHANICAL KILN

Application filed March 29, 1928, Serial No. 265,602, and in Germany February 22, 1927.

This invention relates to a mechanical kiln of the kind comprising a tier of roasting chambers and provided with agitating and propelling vanes connected to carrier arms which, in order to allow the roasting chambers to be very low, are made of horizontal small dimensions and supported at both ends.

The main object of the present invention is to adapt the arms to be effectively cooled by air passing through the arms and through a hollow central shaft, and the invention consists essentially in the provision of arms each of which is formed of a plurality of tubes arranged horizontally in juxtaposition, the central shaft being composed of concentric pipes which communicate with the arm tubes for passing air through the latter.

Another object of the invention is to improve the kiln generally and to save the kiln structure from the detrimental effect of heat as well as to simplify the assembling and the exchange of the different parts.

Various details of construction and combination of parts whereby these and other objects may be achieved are illustrated in the accompanying drawings whereof

Fig. 1 represents a part section of a kiln according to the invention,

Fig. 2, a part section of one of the carrier arms taken in longitudinal direction,

Fig. 3, a section on the line 3—3 of Fig. 2,

Fig. 4, a part section of the arm taken in longitudinal direction,

Fig. 5, a section on the line 5—5 of Fig. 4,

Fig. 6, an end elevation of one of the arm sections,

Fig. 7, a vertical longitudinal section of the outer end of the arm,

Fig. 8, a horizontal section of the same, on the line 8—8 of Fig. 7,

Fig. 9, a sectional view of a carrier arm and the adjacent floors,

Fig. 10, a diagrammatic view shewing the air circulation in the carrier arms and shaft, and

Fig. 11, a modification of Fig. 10.

The kiln is composed in known manner of a plurality of roasting chambers which are superposed on one another and on the heat-

ing source. The chambers are built up of floors 1 having an upper horizontal floor surface and a lower, arched roof for the underlying chamber, the floors being connected into an integral rigid structure. The materials, such as zinc blende or the like, are fed through a hopper 6 into the top chamber of the kiln, and rotating agitating and propelling vanes 18 are provided which shift the materials gradually towards peripheral discharge apertures 2 in one chamber and towards peripheral discharge apertures in the next. While the materials pass downwards through the kiln in this manner, the hot air rises from the heat source and flows through the chambers in the opposite direction so as to effect the roasting of the materials. The gases are discharged through a flue 23.

The vanes 18 are carried by arms which are made of heat, gas and acid-proof metal and which are supported at both ends so that they can be of small dimensions and allow the chambers to be low. The efficiency of the kiln will thereby be greatly enhanced, and the heat will be utilized to the utmost extent.

The carrier arms may be driven from the circumference of the kiln and are connected to a central, hollow shaft 8.

The hollow shaft 8 and a pipe 33, arranged outside and concentrically with the shaft, are made in sections which extend from floor to floor and which are connected by casting 33' as shewn in Figs. 2 and 3. The shaft 8 is supported at the top of the kiln by a ball-bearing 8'. Each carrier arm is composed of three pipes 34 arranged horizontally in juxtaposition and screwed into the casting 33'. The central pipe communicates with the shaft 8, and the outside pipes communicate with the jacket formed by the pipe 33 which latter is covered with a layer of refractory material. The pipes 34 are enclosed, as best shewn in Figs. 7 and 8, in insulating sleeves which are divided into sections and supported on the pipes so as to leave intervening spaces. Sleeve sections 37 carrying vanes 18 alternate with sleeve sections 36 serving as spacing elements. Packing rings 38 are arranged in the joints between the sleeve sections so as to

render the joints tight. Capping pieces 35, through which the pipes 34 communicate with each other, terminate their arms. By this arrangement air passages are formed which may be utilized in different ways. Figs. 10 and 11 illustrate diagrammatically two circulating systems. In Fig. 10 the pipe 33 is closed at the top and open at the bottom. It has also a transverse partition 50 under the second set of arms. The shaft 8 is closed at the lower end and contains a throttle valve 51 whereby the air admission to the lower sets of arms can be regulated. The pipe 33 has discharge aperture 24 situated between the first and second set of arms. Air is fed from the shaft 8 through the centre pipes of the arms and returns to the pipe 33 through the outside pipes of the arms. The air from the first and second set of arms is discharged through apertures 24 into the roasting chambers. From the lower sets of arms air is discharged at the lower end of the pipe 33. In the arrangement of Fig. 11 the pipe 33 is closed at the bottom as well as at the top, and the shaft 8 has a transverse partition 52 which compels the air from the third set of arms to pass through the fourth set of arms as well, outwards through the outer pipes 34, and inwards into the shaft 8 through the centre pipe 34, the air being discharged at the lower end of the shaft 8. In the upper part of the kiln, the air circulation is the same as in Fig. 10. Where the air passes at a considerable speed through two sets of arms in succession, a great cooling effect will be obtained.

The capping pieces 35 are each formed with a flange 39 whereby the arms are connected to the carrier ring 14. This flange may also carry a toothed ring 40 adapted to mesh with a driving pinion.

The arrangement just described has the advantage, apart from the improved air circulation, that the arms can be taken to pieces and their parts renewed without disturbing any of the roasting floors. For this purpose it is only necessary to remove the capping piece 35 whereupon the different tubes and sleeves can be disassembled and detached from the casing 33'.

A further development of the invention is shewn in Fig. 9. The capping piece 35 carries an annular sand channel 46 into which dips a ring 48 connected to the kiln floor next above. A similar sand channel 47, which is bounded at the outside by a ring 49, is made in the floor next below the arms. Into the latter channel dips a cylindrical, sectional ring 43 carried by the capping piece 35. A flat sectional ring 42, arranged inside the ring 43 and connected to the latter, carries a refractory lining 44 which acts as an insulation between the kiln chamber and the atmosphere. By this arrangement the rings 14 and 40 will be effectively protected from the heat.

The rings 48 and 49 can be shifted so as to provide a free passage for the capping pieces 35 and the ring sections 42, 43, when a removal of any arms is required. The ring 43 is provided with inspection apertures 45. The carrier ring 14 is supported by means of balls 41 on suitable races and may be guided by rollers 22.

I claim:

1. A mechanical kiln of the character described, comprising a tier of roasting floors, a hollow, rotatable shaft composed of concentric pipes passing centrally through the floors, arms carried radially by the shaft in the spaces between the floors, each arm being composed of a plurality of tubes arranged in juxtaposition in a horizontal plane, the tubes of the arms and the pipes of the shaft being in communication so as to allow air to be circulated through the same, insulating sleeves threaded on the arms, agitating and propelling vanes carried by said sleeves and means for supporting the outer ends of the arms so as to allow free movement thereof. 75

2. A kiln as claimed in claim 1 wherein a central tube in each arm communicates with a central pipe of the shaft, and wherein outer arm tubes communicate with said central tube and with an outer shaft pipe. 90

3. A kiln as claimed in claim 1 wherein the shaft, arms and insulating sleeves are composed of detachable sections and wherein the sleeve sections are supported on the tubes so as to form intervening spaces between the sleeves and tubes. 95

4. A kiln as claimed in claim 1 wherein the shaft, arms and insulating sleeves are composed of detachable sections, and wherein the sleeve sections are supported in the tubes so as to form intervening air spaces between the sleeves and tubes, and packings interposed between adjacent ends of sleeve sections for tightening the joints. 105

5. The structure claimed in claim 1 and a capping piece, through which the tubes communicate with one another, terminating each arm structure. 110

6. A kiln as claimed in claim 1 wherein the shaft is formed with apertures in the upper part of the kiln structure for discharging air into the spaces between the floors. 115

7. A kiln as claimed in claim 1 wherein the supporting means for the outer ends of the arms consist of rings, capping pieces terminating the outer ends of the arms, flanges on said capping pieces connecting the latter to the supporting rings, and rollers whereon the rings are supported. 120

8. A kiln as claimed in claim 1 wherein the supporting means for the outer ends of the arms consist of rings, capping pieces terminating the outer ends of the arms, flanges on said capping pieces connecting the latter to the supporting rings, rollers whereon the rings are supported, a sand channel carried 125

5 by the supporting ring of each set of arms, a sealing ring connected to the roasting floor above the channel so as to dip into the latter, a sealing ring carried by the same supporting ring so as to form a circumferential closure for the respective roasting chamber, and a sand channel on the underlying floor co-operating with said latter sealing ring for sealing the chamber.

10 9. A kiln as claimed in claim 1 wherein the supporting means for the outer ends of the arms consist of rings, capping pieces terminating the outer ends of the arms, flanges on said capping pieces connecting the latter to the supporting rings, rollers whereon the rings are supported, a sand channel carried by the supporting ring of each set of arms, a sealing ring connected to the roasting floor above the channel so as to dip into the latter, 15 a sealing ring carried by the same supporting ring so as to form a circumferential closure for the respective roasting chamber, a sand channel on the underlying floor co-operating with said latter sealing ring for sealing the chamber, and a heat insulation carried 20 by said latter sealing ring.

25 10. The kiln structure claimed in claim 1 in combination with a ball bearing supporting the shaft at the top of the kiln.
